UNITED STATES PATENT OFFICE

121,602

DESIGN FOR A TUMBLER

James E. Spence, Wheeling, W. Va., assignor to
Hazel-Atlas Glass Company, Wheeling, W. Va.,
a corporation of West Virginia

Application May 29, 1940, Serial No. 92,687

Term of patent 7 years

To whom it may concern:

Be it known that I, James E. Spence, a citizen of the United States, residing at Wheeling, in the county of Ohio and State of West Virginia, have invented a new, original, and ornamental Design for a Tumbler, of which the following is a specification, reference being had to the accompanying drawing, forming part thereof.

Figure 1 is a perspective view of the tumbler, showing my new design, and

Figure 2 is a horizontal sectional view taken on line 2—2 of Figure 1.

I claim:

The ornamental design for a tumbler, as shown.

JAMES E. SPENCE.
